UNITED STATES PATENT OFFICE

ERNEST H. COX, OF DUNCAN, OKLAHOMA

OIL-WELL-TESTING DEVICE

Application filed February 4, 1927. Serial No. 165,984.

This invention relates to well drilling apparatus and has special reference to means for testing wells in order to ascertain whether or not oil, water, or the like are in the path of the hole being drilled, i. e., in the stratum which has been reached by the drill bit but which has not as yet been bored through. The invention disclosed herein is an improvement over my prior Patent No. 1,347,534, granted July 27, 1920.

An object of the invention resides in the provision of a simple and inexpensive means by which a sample of the oil, sand, water or the like at the bottom of the hole being bored may be brought to the surface for examination and analysis prior to the time of sinking the expensive well casing which is ordinarily provided.

Another object of the invention resides in the construction of such a device combined with an effective and reliable device which will function to shut off slush, mud, water, etc., which is in the bottom of the well from the liquid in the lower stratum from which the sample is to be taken.

Other objects and advantages of the invention will be apparent from the following description when taken in connection with the accompanying drawing; in which

Figure 1 is a vertical longitudinal section through the testing device.

Figure 2 is an elevational view thereof.

Figure 3 is a section taken on line 3-3 of Figure 1.

Figure 4 is a section taken on line 4-4 of Figure 1.

Figure 5 is a sectional view through the apparatus when the openings 14 and 15 are in registration; and

Figure 6 is a section taken on line 6-6 of Figure 1.

Referring to the drawing in greater detail the numeral 1 designates a drill stem of any ordinary or conventional form and to the lower end of which is threadedly or otherwise attached my novel testing device referred to generally by the numeral 2.

The testing device consists primarily of a tubular member 3 provided with a head 4 and a shoulder or abutment 5, threads 6 being

formed on the head for engagement with similar threads formed on the lower section of the drill stem 7.

Slidably mounted on the tubular member 3 is a sleeve 8 and encircling the upper end 55 of this sleeve is a pipe section 9 which has its upper end threaded to the upper end of the sleeve. A rubber stopper or the like 10 is fixed on the pipe section 9 and a nipple 11 is threaded to the lower end of this section. 60

As indicated in Figure 1 of the drawing a coil spring 12 encircles the upper end of the tubular member 3 and has its upper end in engagement with the head 4 and its lower end in engagement with the stopper 10 and sleeve 8. 65

In assembling the device thus far described the nipple 11 is threaded to the stopper or pipe section 9 and this element then slipped over the sleeve 8 and threaded to the upper end thereof. The coil spring 12 is then passed over the tubular member 3 with the upper end encircling the abutment 5. Next the combined sleeve and stopper 8-10 is slid over the lower end of the tubular member 3 against the pressure of spring 12, and the cap 13 is then threaded to the lower end of the member 3. 75

Both the tubular member 3 and the sleeve 8 are provided with symmetrically arranged 80 series of perforations or passages 14 and 15 respectively and in order that the series of perforations may always be maintained in perfect alignment a key 16 extends inwardly of the sleeve 8 and is received in the longitudinally extending slot 17 formed in the lower end of the outer wall of the tubular member 3. 85

In operation, the parts being in the position shown in Figure 1, with the perforations 14 and 15 out of registration due to the fact that the spring 12 is forcing the sleeve 8 downwardly so that the sleeve 8 is in engagement with the cap 13, the device is lowered into the hole being drilled until the stopper 10 engages the small pocket previously formed at the bottom of the well by means of the drill bit. Engagement of the stopper with the walls of the pocket will of course limit further downward movement of the 13

sleeve 8 which is secured to the stopper 10. The weight of the drill stem however, will cause the tubular member 3 to continue its downward movement against the pressure of spring 12 until the shoulder 5 comes into engagement with the upper end of the sleeve 8. When this relative movement of the sleeve 8 and tubular member 3 takes place the perforations 14 and 15 will register and a sample of the oil or other liquid in the pocket will pass into the interior of the tubular member. In this position of the parts the stopper 10 will of course seal off the mud, slush, etc., above the perforations 14-15 thereby preventing the entrance of any of this undesirable matter into the testing device while the perforations are in register. Raising of the drill bit and testing device will allow the spring 12 to move the sleeve 8 downwardly with respect to the tubular member and thus close the passages 14-15, whereby the sample of the material may be carried to the top of the well.

Due to the construction and operation just described it will be apparent that the present device is of especial value in testing wells for the reason that uncontaminated samples of the liquid may be readily obtained previous to the process of installing the expensive well casing. It will also be observed that the construction itself is simple and reliable in operation, of few parts which may be readily assembled, and that the entire device is comparatively inexpensive.

In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a device of the class described a tubular member adapted to be secured to the lower end of a drill stem, a sleeve encircling said tubular member and mounted for sliding movement with respect thereto, a stopper and packer element also encircling said tubular member and secured to the upper end of said sleeve, said tubular member and sleeve provided with perforations adapted to register when the sleeve is at the upper limit of its sliding movement, and means normally holding said sleeve in a position in which said perforations are out of register.

2. In a device of the class described a tubular member adapted to be secured to the lower end of a drill stem, a sleeve encircling said tubular member and mounted for sliding movement with respect thereto, a rubber stopper also encircling said tubular member and secured to the upper end of said sleeve, a

coil spring encircling said tubular member and having one end in engagement with the upper end of said stopper and its other end in engagement with an abutment on said tubular member, said tubular member and sleeve provided with perforations adapted to register when the sleeve is at the upper limit of its sliding movement.
